UNITED STATES PATENT OFFICE.

FRANK Y. WILHOFT, OF NEW YORK, N. Y.

VAGINAL SYRINGE.

SPECIFICATION forming part of Letters Patent No. 681,010, dated August 20, 1901.

Application filed May 31, 1901. Serial No. 62,467. (No model.)

To all whom it may concern:

Be it known that I, FRANK Y. WILHOFT, a citizen of the United States, and a resident of New York city, county and State of New

5 York, have invented certain new and useful Improvements in Vaginal Syringes, of which the following is a specification.

This invention relates to a vaginal syringe provided with a nozzle of peculiar construction by which a thorough washing of the vagina is effected.

In the accompanying drawings, Figure 1 is a longitudinal section of my improved vaginal syringe, showing the flexible bulb partly broken away; Fig. 2, a side view of the nozzle *c*; Fig. 3, a side view of the tube *b*. Fig. 4 represents several details of the wheel *e* and sleeve *d*, and Fig. 5 is an enlarged end view of the nozzle.

20 The letter *a* represents the soft-rubber bulb of the syringe, into the neck of which is fitted the tube *b*, having a threaded upper end for engagement with the threaded nozzle *c*. This nozzle is made of bulged form and is provided 25 with a central opening into which is fitted a flanged sleeve *d*. The sleeve *d* contains a rotatable wheel *e*, having inclined blades *e'* and turning on a screw-pivot *f*, that is tapped into a transverse bridge-piece or lug *d'* of the 30 sleeve. By tightening up the screw-pivot more or less the force of the spray emitted may be regulated. The wheel *e* is by the con-

struction described set within the body of the nozzle, and may thus rotate freely without coming into contact with the walls of the 35 vagina.

Around the wheel *e* the nozzle *c* is provided with a series of lateral perforations *g* and *h*, arranged, preferably, in two or more concentric rows. These perforations or bores incline 40 in opposite directions from the axis of the syringe, Fig. 5, the perforations *g* slanting from left to right and the perforations *h* slanting from right to left. Thus the liquid contents of the bulb *a* will be forced out at the 45 circumference of the nozzle in two diverging streams, while centrally through these streams passes the axial spray formed by the inclined blades of the rotating wheel *e*. The effect of the combined action of these differently-deflected jets is to subject the vagina to a thorough 50 cleansing.

What I claim is—

A vaginal syringe provided with a nozzle containing a rotatable wheel, and with perforations around said wheel that slant in opposite directions, substantially as specified. 55

Signed by me at New York city, county and State of New York, this 27th day of May, 1901.

FRANK Y. WILHOFT.
